UNITED STATES PATENT OFFICE

161,312

TABLE TOP OR SIMILAR ARTICLE

Ben Bunin, River Edge, N. J., assignor to Product
Design & Mfg. Corp., North Hackensack, N. J.

Application June 19, 1950, Serial No. 10,615

Term of patent 7 years

(Cl. D33—14)

To all whom it may concern:

Be it known that I, Ben Bunin, a citizen of the United States, residing at River Edge, in the county of Bergen and State of New York, have invented a new, original, and ornamental Design for a Table Top or Similar Article, of which the following is a specification, reference being had to the accompanying drawing, forming a part thereof.

Fig. 1 is a plan view of a table top or similar article, showing my new design.

Fig. 2 is a side elevational view thereof.

I claim:

The ornamental design for a table top or similar article, substantially as shown.

BEN BUNIN.
